MACHINE FOR SHAPING UPPERS OVER
LASTS

Bernhardt Jorgensen, Marblehead, Mass., assignor to United Shoe Machinery Corporation, Flemington, N. J., a corporation of New Jersey

Application September 23, 1941, Serial No. 411,996

23 Claims. (Cl. 12—4)

This invention relates to machines for use in the manufacture of shoes for shaping uppers over lasts, and is herein illustrated as applied to a pulling-over machine of a well-known type the main characteristic features of which are disclosed in United States Letters Patent No. 1,029,387, granted on June 11, 1912, on an application of R. F. McFeely's. It is to be understood, however, that in its more general aspects the invention is not limited to machines of that particular type.

It has been proposed heretofore to provide pulling-over machines with means for effecting a series of rapidly repeated relative upper-pulling movements of the upper-gripping means and the last, since in this manner an upper may be very effectively stretched and conformed to the contour of the last. The present invention provides novel means particularly well adapted for successful results in such treatment of uppers whatever may be the characteristics of different uppers. As herein illustrated, the upper-pulling force thus applied is transmitted through a body of fluid confined in a chamber and preferably noncompressible, the machine having a reciprocating member which sets up in the body of fluid a series of rapidly repeated pressure impulses and having mechanism movable by the impulses of the fluid to effect the pulling of the upper. In the construction shown this mechanism is arranged to operate grippers which pull the upper at the opposite sides of the last, but it will be understood that in its more general aspects the invention is not limited to gripper-operating means or to means for pulling an upper in those particular locations. The invention further provides for progressively increasing the volume of the fluid in the above-mentioned chamber, so that the upper is stretched with progressively increasing force by the impulses of the fluid, and means for limiting the force of the pull by limiting the pressure of the fluid in the chamber. In the illustrated embodiment of the invention the means for thus pulling the upper repeatedly serves as supplemental upper-pulling means, combined with means for first applying to the upper a single continuous pull in a stage of a cycle of power operations of the machine in the manner characteristic of machines of the type shown in the previously mentioned Letters Patent, the action of the supplemental means on the upper being automatically initiated near the end of that stage of the cycle and continuing thereafter in a pause which occurs in the cycle. In the provision of means for thus pulling the upper ini-

5 tially and means for thereafter subjecting it to a series of supplemental pulling impulses which are automatically initiated, the invention is not limited to supplemental upper-pulling means in which the upper-pulling force is transmitted through a body of fluid as herein illustrated.

The above and other features of the invention, including various novel details of construction and combinations of parts, will now be more particularly described with reference to the accompanying drawings and thereafter pointed out in the claims.

In the drawings,

Fig. 1 is a view mainly in left-hand side elevation of the upper portion of a pulling-over machine of the previously mentioned type with the present invention embodied therein;

Fig. 2 is a similar view on a larger scale of a portion of the structure;

Fig. 3 is mainly a perspective view of the upper-pulling means with the parts in the positions which they occupy when the upper is being pulled repeatedly by the side grippers; and

Fig. 4 is a view partly in left-hand side elevation and partly in vertical section of a portion of the means provided for pulling the upper repeatedly, with the parts positioned as in Fig. 3.

Like prior machines of the illustrated type, the machine herein shown is provided with a toe-end gripper 2 and opposite side grippers 4 (Fig. 3) which grip and pull an upper over a last respectively at the end of the toe and the sides of the forepart, the last being supported against the pull of the grippers by a shoe rest 6 which commonly engages the forepart of an insole on the last. The side grippers 4 are connected to gripper-operating levers 8 which are mounted to swing about a fulcrum rod 10 and to which upper-pulling movements are imparted by downward movement of a cam-operated slide 12. The slide is connected to the levers through rods 14 and springs 16, these springs being yieldable independently of each other in response to resistance of the upper to the force of the pull applied thereto respectively by the different grippers. The toe-end gripper 2 is operated by mechanism not herein shown in detail but similar to that provided for operating each side gripper. In a machine of the illustrated type the grippers are operated to pull the upper in the first stage of a cycle of power operations of the machine, whereupon the machine comes automatically to a stop to permit the operator to inspect the upper and to make any necessary adjustment of it relatively to the last during a pause in the cycle. Near the end of

this first stage of the cycle a heel rest 18 is moved forwardly into supporting engagement with the heel end of the shoe by mechanism including a cam-operated slide 20 which, as the parts are viewed in Fig. 1, moves toward the left thus to operate the heel rest. This slide corresponds to the slide 10 shown in the previously mentioned Letters Patent. When the machine is again started a pair of side clamp arms, one of which is shown at 22 in Fig. 1, are swung inwardly into supporting relation to the shoe, and immediately thereafter a front tacker arm 24 and opposite side tacker arms 26 are swung inwardly toward the shoe into positions for driving tacks to fasten the margin of the upper to the insole and last, only one of the side tacker arms 26 being visible in the drawings. In response to the inward movements of the tacker arms the grippers are tripped to cause them to release the upper. The tacker arms carry wipers, one of which is shown at 28 in Fig. 1, for wiping the margin of the upper inwardly over the insole, and are provided also with tack-driving mechanisms which are operated immediately after the arms complete their inward movements. Thereafter the parts of the machine are returned to their starting positions ready for operation on the next shoe.

For purposes of this invention there is mounted on the left-hand side of the machine a casing 30 so formed as to provide a vertical cylinder 32 in which are mounted a lower piston 34 and an upper piston 36, the lower piston being somewhat smaller in diameter than the upper piston and being mounted in a diametrically reduced portion of the cylinder. Within the cylinder between the two pistons is a chamber 38 filled with fluid which is preferably a noncompressible liquid such as light oil. The casing 30 further serves to provide, outside of the cylinder 32, a reservoir 40 for oil under atmospheric pressure, the level of the upper surface of the oil being above the piston 36. This piston is connected by a pin 42 to an arm 44 fast on a rockshaft 46 mounted in bearings in the casing 30, the arm being located within the reservoir 40. The pin 42 extends through a slot 48 formed in a lug 50 on the piston 36 to permit the necessary play in the movements of the piston. Also fast on the rockshaft 46 outside of the casing 30 is an arm 52 connected by a link 54 to an arm 56 fast on a rockshaft 58 mounted in bearings in the head of the machine. Fast on the shaft 58 is a block 60 which carries a member 62 arranged to bear on the upper faces of the side-gripper-operating levers 8 and connected to these levers by yoke members 64 which extend over the upper face of the member 62 and over the lower faces of the levers 8. The member 62 is provided with a stem 66 mounted to turn in the block 60, so that the member 62 by tipping movements may assume different positions corresponding to different relative positions assumed by the gripper-operating levers 8 in the pulling of the upper. It will be evident that by reason of the connections thus provided between the levers 8 and the rockshaft 58 swinging movements of the levers are necessarily accompanied by turning movement of the rockshaft, and that by upward movements of the piston 36 upper-pulling movements may be imparted to the levers. The rockshaft 58 and the connections between it and the gripper-operating levers 8 are substantially identical with portions of mechanism heretofore provided in machines of the illustrated type for retarding the

initial upper-pulling movement of the side grippers and for controlling them manually, as disclosed in Letters Patent No. 1,169,414, granted on January 25, 1916, on an application of R. F. McFeely's. In the construction herein shown the retarding means and the provision for such manual control are omitted as unnecessary, as more fully hereinafter explained.

Rapidly repeated supplemental upper-pulling movements are imparted to the side grippers 4 by movements of the piston 36 in the pause which occurs in the cycle of operations after the initial pulling of the upper. For thus operating the piston 36 a series of pressure impulses are set up in the fluid in the chamber 38 by rapid reciprocating movements of the piston 34. This piston is connected by a pitman 68 to a crank pin 70 formed eccentrically on a shaft 72 mounted in a bearing on the head of the machine, and fast on the shaft is a pulley 74 connected by a belt 76 to a continuously driven pulley (not shown) operated by the power-driving means at the base of the machine. In order to prevent operative movements from being imparted to the piston 36 until the desired time in the operation of the machine, a passageway 78 (Fig. 4) controlled by a valve 80 is provided between the chamber 38 and the reservoir 40, so that when this valve is open the fluid will flow back and forth in the passageway 78 between the chamber 38 and the reservoir 40 without any operative effect on the piston 36. The valve 80 is provided with a stem 82 movable in a bushing 84 which is threaded in the casing 30. Supported on an extension of the bushing 84 is a bracket 86, and mounted in this bracket between an adjusting screw 88 and a plunger 90 which engages the outer end of the valve stem 82 is a compression spring 92 which acts through the plunger on the valve stem and tends to move the valve toward a valve seat 94 on the cylinder 32 and thus to close the passageway 78. Threaded on the outer end of the valve stem 82 is a spool 96 between two flanges 98 and 100 of which is the forked lower end of a valve-controlling lever 102 hereinafter referred to. To hold the valve 80 initially in position to permit free passage of the fluid between the chamber 38 and the reservoir 40 as above described, there is provided a lever 104 pivotally mounted at 106 (Fig. 1) on a bracket 108 on the head of the machine and having a hooked end 110 arranged to engage the flange 100 of the spool 96 as illustrated in Fig. 1. The lever 104 is held in this valve-controlling position by a spring 112 which tends to swing it upwardly. To render the fluid in the chamber 38 effective to operate the piston 36, the valve 80 is released by downward movement of the lever 104. For this purpose there is fast on the previously mentioned slide 20 an arm 114 provided with a pin 116 arranged to engage an inclined face 118 on the lever 104. When the slide 20 is operated to move the heel rest 18 forwardly into engagement with the shoe near the end of the first stage of the cycle of operations of the machine, the pin 116 by engagement with the inclined face 118 swings the lever 104 downwardly to release the valve 80 which is then moved by the spring 92 to close the passageway 78 and thereby to initiate the series of rapidly repeated supplemental upper-pulling movements of the side grippers.

It will be evident that the upper-pulling movements are imparted to the side grippers by up-

ward movements of the piston 38 in response to corresponding movements of the piston 34 which transmits its force to the piston 38 through the fluid in the chamber 38. It will be further evident that if the piston 38, after each upward movement, were to move downwardly the same distance in response to a corresponding downward movement of the piston 34, substantially no useful result would be obtained in the pulling of the upper by the grippers. It will be understood that the piston 38 is not moved downwardly to that extent by the elasticity of the upper, since the upper is stretched more or less by each pull applied thereto and since the springs 16 by their action on the levers 8 tend to prevent retractive movements of the grippers. In order, therefore, to overcome the tendency for the piston 38 to be moved downwardly in response to the downward movements of the piston 34, provision is afforded for the admission of additional fluid to the chamber 38 from the reservoir 40 in response to the downward movements of the piston 34. For this purpose the piston 38 is provided with a passageway 128 controlled by a check valve 122 which is normally held closed by a spring 124, this spring being mounted between the valve and a nipple 126 which is threaded in the piston and is provided with a passageway 128. Accordingly, downward movements of the piston 34 serve to draw fluid past the valve 122 through the passageways 126 and 128 and thus to increase the volume of the fluid in the chamber 38 as the upper is pulled progressively by the side grippers. It will be evident that as the volume of the fluid thus increases the upper is pulled with increasing force by the upward movements of the piston 38 by reason of the increasing resistance which it offers to the movements of the grippers. Before the pull on the upper becomes excessive the valve 80 is forced away from its seat against the resistance of the spring 92 by the pressure of the fluid in the chamber 38, thus limiting the force of the pull applied to the upper. It will be understood that thereafter the valve is forced away from its seat in response to each upward movement of the piston 34, so that the fluid admitted to the chamber 38 in response to the downward movements of this piston is returned to the reservoir 40 without any substantial further increase in the force of the pull on the upper. The maximum force of the pull may be varied by turning the adjusting screw 88 to vary the stress of the spring 92.

The action of the supplemental gripper-operating means is terminated shortly after the beginning of the final stage of the cycle of operations of the machine by moving the valve 80 away from its seat 84 to provide free passage for the fluid between the chamber 38 and the reservoir 40. This movement of the valve is effected through the previously mentioned lever 102 which, as shown in Fig. 1, is pivotally mounted substantially midway between its opposite ends on a lug 130 formed on the casing 30. Pivotally connected to the upper end of the lever is one end of a rod 132 the other end of which is forked to embrace a boss 134 (Fig. 2) formed on a cam 136 which is secured by a clamping screw 138 to one end of a rockshaft 140 with which a machine of the illustrated type is provided for imparting inward swinging movements to the tacker arms 24 and 26 and for actuating the tack-driving mechanisms. The position of the cam relatively to the rockshaft is determined by a dowel pin 142. The boss 134 is provided with a flange 75

144 for engaging one side of the forked portion of the rod 132 to assist in maintaining the rod in its proper position. The cam 136 is provided with a depression 146 which in the first stage of the cycle of operations is in position to receive a roll 148 carried by the rod 132, so that the valve 80 when it is released by the lever 104 may be moved to its closed position by the spring 92. As soon as the rockshaft 140 begins to turn to impart the inward swinging movements to the tacker arms the cam 136 acts on the roll 148 to swing the lever 102 in a counterclockwise direction (Fig. 1) and thus to move the valve 80 to open position. The valve is maintained by the cam in this position until the lever 104 is swung upwardly by the spring 112 in response to return movement of the slide 20 near the end of the cycle, so that the hooked end 110 of the lever will hold the valve open when the depression 146 of the cam returns to a position opposite the roll 148 at the end of the cycle, as shown in Fig. 2.

The manner of operation of the machine, in so far as it is of interest with reference to the present invention, will now be briefly summarized. It will be understood that the piston 34 is at all times rapidly reciprocated by its operating means, but that prior to the operation of the machine on a shoe this is without any effect on the side grippers, since the valve 80 is held in open position by the lever 104 and the fluid, therefore, flows idly through the passageway 18 between the chamber 38 and the reservoir 40. The movements of the piston are very short movements, since the crank pin 70 is but little displaced from the axis of the shaft 72, as shown in Fig. 1. After presenting a shoe to the machine with the margin of the upper between the jaws of the several grippers, the operator starts the machine, whereupon the grippers are closed and are operated to pull the upper in the first stage of the cycle, the machine thereafter coming to a stop with the grippers holding the upper under tension. The side grippers 4 are thus operated yieldingly through the springs 16 which, in view of the means provided by this invention for thereafter further operating the side grippers, may be lighter springs than commonly used heretofore in machines of the illustrated type. Since the upper is thus subjected by the side grippers to a comparatively light pull in the first stage of the cycle, the means previously referred to as commonly used heretofore for retarding the upper-pulling movements of the side grippers and for controlling them manually is rendered unnecessary and is accordingly dispensed with. Near the end of the first stage of the cycle the heel rest 18 is moved forwardly into engagement with the shoe by the slide 20, and by this movement of the slide the lever 104 is swung downwardly to release the valve 80 and thus to permit it to be closed by the spring 92. As the valve is thus closed the roll 148 (Fig. 2) is moved by the lever 102 and the rod 132 into the depression 146 of the cam 136 on the rockshaft 140. Since the closing of the valve 80 terminates the free flow of fluid through the passageway 18 resulting from the movements of the piston 34, the piston thereafter in its upward movements sets up pressure impulses in the fluid in the chamber 38 and acts thus through the fluid to impart upward movements to the piston 38 and thereby to impart further upper-pulling movements to the grippers 4. Since the upper is stretched more or less by these movements of the grippers and since

the springs 16 tend to prevent reverse movements of the grippers by the elasticity of the upper, the downward movements of the piston 34 serve to draw additional fluid from the reservoir 40 into the chamber 38 past the check valve 42. The volume of the fluid in the chamber 38 is thus progressively increased, so that the upper is stretched with progressively increasing force by the impulses of the fluid in the chamber 38 as its resistance to the movements of the grippers progressively increases. Eventually the pressure of the fluid in the chamber 38 resulting from an upward movement of the piston 34 becomes great enough to force the valve 80 off its seat against the adjustably variable resistance of the spring 92, permitting fluid to be forced from the chamber into the reservoir 40 without operating the piston 36. The limit of force with which it is desired to pull the upper through the side grippers having thus been reached, the valve 80 is thereafter forced off its seat by each upward movement of the piston 34, so that the upper is not subjected to any substantial further pull but is nevertheless maintained under the desired tension.

It will be understood that the above-described supplemental upper-pulling movements of the side grippers, which are initiated substantially at the end of the first stage of the cycle of operations of the machine, take place mainly during the pause in the cycle when the machine is otherwise idle and when the operator is permitted to inspect the upper and if necessary to adjust it relatively to the last. After the machine has again been started and the side clamp arms 22 have been swung inwardly into positions to control the shoe, the rockshaft 140 is turned to swing the tacker arms 24, 26 inwardly toward the shoe and then to actuate the tack-driving mechanisms, the several grippers being tripped to cause them to release the upper as the tacker arms are thus swung inwardly, as disclosed in Letters Patent No. 1,029,387. In response to this movement of the rockshaft 140 the cam 136 acts through the rod 132 and the lever 102 to move the valve 80 to its open position, thus again permitting a free flow of fluid through the passageway 78 and rendering the fluid ineffective on the piston 36 notwithstanding the continued movements of the piston 34. When the slide 20 receives its return movement near the end of the cycle, the lever 104 is swung upwardly by the spring 112 into position again to engage the flange 100 and thus to maintain the valve 80 in its open position after the rockshaft 140 has returned the cam 136 to the initial position in which it is shown in Fig. 2.

Having described the invention, what I claim as new and desire to secure by Letters Patent of the United States is:

1. In a machine for shaping uppers over lasts, means for gripping the margin of an upper on a last, a device having a body of fluid therein, means for setting up in said body of fluid a series of automatically repeated pressure impulses, and mechanism for effecting a series of relative movements of said upper-gripping means and the last to pull the upper in response to the impulses thus set up in the fluid.

2. In a machine for shaping uppers over lasts, means for gripping the margin of an upper on a last, a device provided with a chamber having a body of fluid therein, a member arranged to act on the fluid in said chamber, means for reciprocating said member to set up in said body

of fluid a series of automatically repeated pressure impulses, and mechanism movable by the impulses thus set up in the fluid to effect a series of relative upper-pulling movements of said upper-gripping means and the last.

3. In a machine for shaping uppers over lasts, means for gripping the margin of an upper on a last, a fluid-containing cylinder, a piston in said cylinder, means for reciprocating said piston to set up in the fluid a series of automatically repeated pressure impulses, another piston in said cylinder movable by the impulses of said fluid, and mechanism for effecting by the movements of said other piston a series of relative upper-pulling movements of said upper-gripping means and the last.

4. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for effecting by the movements of said other member a series of relative upper-pulling movements of said upper-gripping means and the last, and spring means tending to prevent reverse relative movements of said upper-gripping means and the last during the movements of said first-named member in one direction.

5. In a machine for shaping uppers over lasts, grippers arranged to grip the margin of an upper on a last at the opposite sides of the last respectively, a device provided with a chamber having a body of fluid therein, a member arranged to act on the fluid in said chamber, means for operating said member to set up in said body of fluid a series of automatically repeated pressure impulses, another member movable by the impulses of said fluid, and mechanism for imparting to said grippers by the movements of said other member a series of movements to pull the upper over the last.

6. In a machine for shaping uppers over lasts, grippers arranged to grip the margin of an upper on a last at the opposite sides of the last respectively, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for imparting to said grippers by the movements of said other member a series of movements to pull the upper over the last, and springs associated respectively with said different grippers and tending to prevent reverse movements thereof during the movements of said first-named member in one direction.

7. In a machine for shaping uppers over lasts, grippers arranged to grip the margin of an upper on a last at the opposite sides of the last respectively, a fluid-containing cylinder, a piston in said cylinder, means for reciprocating said piston to set up in the fluid a series of automatically repeated pressure impulses, another piston in said cylinder movable by the impulses of said fluid, and mechanism for imparting to said grippers by the movements of said other piston a series of movements to pull the upper over the last.

8. In a machine for shaping uppers over lasts,

means for gripping the margin of an upper on a last, a device provided with a chamber having a body of fluid therein, means for setting up in said body of fluid a series of automatically repeated pressure impulses while progressively increasing the volume of the fluid in said chamber, and mechanism arranged to be operated by the impulses of said fluid to effect a series of relative movements of said upper-gripping means and the last to pull the upper with progressively increasing force as the volume of the fluid in said chamber increases.

9. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, mechanism including another member movable by the impulses of said fluid to effect a series of relative upper-pulling movements of said upper-gripping means and the last, and means for admitting additional fluid to said chamber in response to movements of said first-named member in one direction to increase progressively the volume of the fluid in the chamber as the upper is stretched by the series of pulls applied thereto.

10. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, mechanism including another member movable by the impulses of said fluid to effect a series of relative upper-pulling movements of said upper-gripping means and the last, a fluid reservoir, and a check valve arranged to open to admit additional fluid from the reservoir to said chamber in response to movements of said first-named member in one direction to increase progressively the volume of the fluid in said chamber as the upper is stretched by the series of pulls applied thereto.

11. In machine for shaping uppers over lasts, means for gripping the margin of an upper on a last, a device provided with a chamber having a body of fluid therein, means for setting up in said body of fluid a series of automatically repeated pressure impulses, mechanism arranged to be operated by the impulses of said fluid to effect a series of relative movements of said upper-gripping means and the last to pull the upper with progressively increasing force, and means for automatically limiting the force thus applied to the upper.

12. In a machine for shaping uppers over lasts, means for gripping the margin of an upper on a last, a device provided with a chamber having a body of fluid therein, means for setting up in said body of fluid a series of automatically repeated pressure impulses while progressively increasing the volume of the fluid in said chamber, mechanism arranged to be operated by the impulses of said fluid to effect a series of relative movements of said upper-gripping means and the last to pull the upper with progressively increasing force as the volume of the fluid in said chamber increases, and means for automatically limiting the pressure of the fluid in said chamber to limit the force thus applied to the upper.

13. In a machine for shaping uppers over lasts, means for gripping the margin of an upper on a last, a device provided with a chamber having a body of fluid therein, means for setting up in said body of fluid a series of automatically repeated pressure impulses while progressively increasing the volume of the fluid in said chamber, mechanism arranged to be operated by the impulses of said fluid to effect a series of relative movements of said upper-gripping means and the last to pull the upper with progressively increasing force as the volume of the fluid in said chamber increases, and spring-controlled valve means arranged to provide an outlet for the fluid from said chamber to limit the force thus applied to the upper.

14. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for effecting by the movements of said other member a series of relative upper-pulling movements of said upper-gripping means and the last, valve means for admitting additional fluid to said chamber in response to movements of said first-named member in one direction to increase progressively the volume of the fluid in the chamber and thus to increase the force of the pull applied to the upper, and additional spring-controlled valve means arranged to provide an outlet for the fluid from said chamber to limit the pressure of the fluid and thereby to limit the force of the pull on the upper.

15. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for effecting by the movements of said other member a series of relative upper-pulling movements of said upper-gripping means and the last, a fluid reservoir, a check valve arranged to open to admit additional fluid from the reservoir to said chamber in response to movements of said first-named member in one direction to increase progressively the volume of the fluid in said chamber and thus to increase the force of the pull applied to the upper, and a spring-controlled valve movable to permit return of fluid from the chamber to said reservoir to limit the pressure of the fluid in the chamber and thereby to limit the force of the pull on the upper.

16. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for effecting by the movements of said other member a series of relative upper-pulling movements of said upper-gripping means and the last, means providing a passageway for flow of the fluid into and out of said chamber to render the fluid ineffective on said other member regardless of the movements of said first-named member, and means for initi-

ating the operative movements of said other member by obstructing the flow of fluid in said passageway.

17. In a machine for shaping uppers over lasts, means for gripping the margin of an upper on a last, a device provided with a chamber having a body of fluid therein, a member arranged to act on the fluid in said chamber, means for reciprocating said member to set up in said body of fluid a series of automatically repeated pressure impulses, another member movable by the impulses of said fluid, mechanism for effecting by the movements of said other member a series of relative upper-pulling movements of said upper-gripping means and the last, a fluid reservoir, means providing a passageway for flow of the fluid between said chamber and reservoir to render the fluid ineffective on said other member regardless of the movements of said first-named member, a valve movable into position to obstruct the flow of fluid in said passageway and thus to render the fluid effective on said other member, a spring for thus moving the valve, and means for holding the valve initially retracted against the resistance of said spring and for releasing it to the action of the spring.

18. In a machine for shaping uppers over lasts, means for gripping the margin of an upper on a last, operating means for effecting relative movement of said upper-gripping means and the last to pull the upper in a stage of a cycle of power operations of the machine and for then holding the upper under tension during a pause in the cycle, supplemental operating means for effecting automatically in said pause in the cycle a series of relative movements of said upper-gripping means and the last further to pull the upper, and automatic means for initiating the upper-pulling action of said supplemental operating means.

19. In a machine for shaping uppers over lasts, means for gripping the margin of an upper on a last, operating means for effecting relative movement of said upper-gripping means and the last to pull the upper in a stage of a cycle of power operations of the machine and for then holding the upper under tension during a pause in the cycle, supplemental operating means for effecting automatically in said pause in the cycle a series of relative movements of said upper-gripping means and the last further to pull the upper, and automatic means for initiating and for terminating the effective action of said supplemental operating means prior to and after said pause in the cycle respectively.

20. In a machine for shaping uppers over lasts, grippers arranged to grip the margin of an upper on a last at the opposite sides of the last respectively, operating means for moving said grippers to pull the upper in a stage of a cycle of power operations of the machine and for then maintaining them in positions to hold the upper under tension during a pause in the cycle, supplemental operating means for imparting to said grippers automatically in said pause in the cycle a series of additional upper-pulling movements,

and automatic means for initiating the action of said supplemental operating means on the grippers in said upper-pulling stage of the cycle.

21. In a machine for shaping uppers over lasts, means for gripping the margin of an upper on a last, operating means for effecting relative movement of said upper-gripping means and the last to pull the upper in a stage of a cycle of power operations of the machine and for then holding the upper under tension during a pause in the cycle, a device having a body of fluid therein, means for setting up in said body of fluid a series of automatically repeated pressure impulses, and mechanism for effecting in said pause in the cycle a series of relative movements of said upper-gripping means and the last further to pull the upper in response to the impulses thus set up in the fluid.

22. In a machine for shaping uppers over lasts, means for gripping the margin of an upper on a last, operating means for effecting relative movement of said upper-gripping means and the last to pull the upper in a stage of a cycle of power operations of the machine and for then holding the upper under tension during a pause in the cycle, a device provided with a chamber having a body of fluid therein, a member arranged to act on the fluid in said chamber, means for reciprocating said member to set up in said body of fluid a series of automatically repeated pressure impulses, mechanism movable by the impulses thus set up in the fluid to effect in said pause in the cycle a series of relative movements of said upper-gripping means and the last further to pull the upper, and automatic means for initiating the upper-pulling action of the fluid on said mechanism in said upper-pulling stage of the cycle.

23. In a machine for shaping uppers over lasts, means for gripping the margin of an upper on a last, operating means for effecting relative movement of said upper-gripping means and the last to pull the upper in a stage of a cycle of power operations of the machine and for then holding the upper under tension during a pause in the cycle, a device provided with a chamber having a body of fluid therein, a member arranged to act on the fluid in said chamber, means for reciprocating said member to set up in said body of fluid a series of automatically repeated pressure impulses, mechanism including another member movable by the impulses thus set up in the fluid to effect in said pause in the cycle a series of relative movements of said upper-gripping means and the last further to pull the upper, means providing a passageway for flow of the fluid into and out of said chamber to render the fluid ineffective on said other member regardless of the movements of said first-named member, a valve movable into position to obstruct the flow of the fluid in said passageway and thus to render the fluid effective on said other member, and automatic means for thus moving said valve in said upper-pulling stage of the cycle.

BERNHARDT JORGENSEN.
